UNITED STATES PATENT OFFICE.

CHARLES E. RANDALL, OF BOSTON, MASSACHUSETTS, ASSIGNOR TO THE
HANCOCK INSPIRATOR COMPANY, OF SAME PLACE.

INJECTOR.

SPECIFICATION forming part of Letters Patent No. 378,403, dated February 21, 1888.

Application filed September 6, 1886. Serial No. 212,845. (Model.)

To all whom it may concern:

Be it known that I, CHARLES E. RANDALL, of Boston, in the county of Suffolk, and in the State of Massachusetts, have invented certain new and useful Improvements in Injectors for Feeding Water to Steam-Boilers; and I do hereby declare that the following is a full, clear, and exact description thereof, reference being had to the accompanying drawings, in

which—

Figure 1 shows a sectional view of the "Hancock inspirator," as known to the trade, with my invention applied thereto; and Fig. 2, a detail view of a modified form of valve.

Letters of like name and kind refer to like parts in each of the figures.

The object of my invention is to provide an improvement on the Hancock inspirator, as shown and described in United States Patent

No. 185,861, January 2, 1877; and my invention relates particularly to an improved steam-admission valve and ports in the same, whereby the admission of steam to the apparatus is controlled by the operator; and to this end my invention consists in the improvements as hereinafter set forth and more particularly pointed out in the claims.

In the drawings, A A' and B B' designate the lifting-tubes of the inspirator, and C C' and D D' the forcing-tubes of the same.

The passages and conduits for admitting and conducting the steam to the lifting and forcing tubes and the water-supply overflow and delivery-conduits need not be particularly described herein, as they can be much varied without departure from my invention.

E designates the steam-supply passage adapted to be connected by a suitable pipe with the boiler. Cutting off this passage from the 40 passage E', for conducting the steam to the lifter steam-tube A A' of the lifter, is the partition F, having in it the port f. A valve, F', attached to stem G, serves to open and close this port. Said port is on its inner side pro-

vided with the conical valve-seat f', and the valve itself is provided with a correspondingly-shaped seating-surface, f'', to engage such seat. Rigidly connected with valve F', by means of the stem G, is the piston-valve head H, fitting and sliding in the cylindrical passage H' between the space h, which communicates

with the valve-port f when valve F' is opened, and the passage K, for conducting steam to the forcer. At the sides of the valve-passage H' are ports h' h', communicating with the steam- 55 passage K. With this construction, when the valve F' is seated so as to close port f, steam is shut off from both the lifter and forcer tubes.

As a means for moving the valves F' and H, I have provided the outwardly-projecting stem 60 L, connected with them, threaded at L', and at its outer end provided with a suitable turning handle, L''. This stem passes through a threaded nut, L', screwed to the casing, the threaded portion of the stem engaging the 65 threads within the nut. A stuffing-box cap, M, fits the stem and is screwed upon the outer end of nut L'.

The valve F' is smaller in area than the piston-valve head H, as shown clearly in the 70 drawings, and is on the side of its valve-port opposite to the entrance chamber or passage for the steam from the source of supply. The result of this construction and arrangement is that as the valve is being seated the steam- 75 pressure against the end of the valve is only proportional to the smallest area of the valve-seat, so that there is less wear upon the screw-thread of the valve-stem than in the double-seated valves heretofore used for the same 80 purpose.

Where, as heretofore, the valve for shutting off the steam from the lifting or forcing devices, or both, has been placed on the steam-admission side of the valve-port, the pressure 85 of the steam has been brought to bear directly upon the greatest area of the valve-head when the valve was closed.

As the area of the valve pressed upon by the steam was necessarily large, the pressure upon 90 the valve when closed or nearly closed has been so great as to cause much wear of the screw-threads on the stem, as well as to make the movement of the valve different.

With my construction and arrangement of 95 valves the smallest area of the valves is presented to the pressure of the entering steam, so that the movement of the valve is made much more easy than with the valves arranged as heretofore—for instance, as in Letters Patent No. 100 239,326, dated March 29, 1881.

The full pressure of the steam from the boiler

does not act upon the piston-valve H, as when valve F' is open the steam has free passage down through the tube or passage E' to the lifter-tubes.

- 5 I have shown my injector as provided with an intermediate overflow-valve, O, on the threaded stem O' whose threaded portion passes through a threaded nut, O². The outer portion of the stem passes through a stuffing-
10 cap, O³, screwed on the the nut O² and fitting the stem, and its outer end is provided with a suitable handle, O⁴. The valve itself is preferably made conical, as shown, the valve-seat O⁵ therefor being correspondingly shaped.
15 The valve opening or port closed by the valve O connects the water-passage around the forcing-tube D D' with the passage into which the discharge or lower end of such tube opens and which is connected with the delivery and over-
20 flow pipes or passages, as shown.

The pipe marked "overflow" on the drawings is to have the usual final overflow-valve, though such is not shown.

- 25 The operation of the injector with the valves, as shown and described hereinbefore, is as follows: The intermediate and final overflow-valves being open and the valve F' being closed, when the operator gives the valve-stem L' a slight turn steam is admitted directly to the lifting injector-tubes, and the air will be expelled from the apparatus and exhausted from the suction-pipe communicating with the well or other source of supply of water. Water will then be drawn from the well through the
30 suction-pipe, and passing through the apparatus will be discharged through the open overflow-valves. The intermediate overflow-valve, O, is then closed and the valve-stem L' is turned farther, so that the piston-valve
35 head H opens the ports h' h', admitting the steam into passage K, and so to the forcing injector-tubes C C' and D D'. The forcing part of the injector having been thus thrown into operation, the final overflow-valve is closed, and the full current will be established through the delivery-pipe and water will be fed into the boiler. The final overflow-valve, which is such as is always provided with an inspirator, can be, if desired, located
45 directly on or in the delivery-pipe instead of on the overflow-pipe, arranged as shown in the drawings, and connected with the delivery-pipe.

- 50 Instead of employing the piston valve H as a second valve, a puppet-valve similar to valve F' can be used, as shown in Fig. 2. In this case the prolongation of the stem L at G is made to slide through the second valve, so that the first or inlet valve can be opened before the second valve. A pin, g, on the portion G of the stem will, by the movement of the stem through the second valve, be brought into contact with the valve to move it. A flat spring or elastic washer of metal or rubber is placed around the stem between the second valve and a shoulder on the stem to allow

of the proper seating of both valves in case they should not be accurately adjusted when made or should wear unevenly.

Having thus described my invention, what I claim is—

1. In an injector provided with the steam-inlet-valve opening, the passage h, in communication with the lifter steam-jet tube, and a port or ports connecting such passage with a 75 passage leading to the force steam-jet tube, the valve for closing the inlet-valve opening on the inner side thereof, the valve for closing port or ports leading from passage h, connected rigidly with the former valve, and 80 means for moving the valves, substantially as and for the purpose specified.

2. In an injector provided with the inlet-port f, the passage h, into which the port admits steam, and one or more ports, h', opening from such passage, the valve F', for closing the discharge side of the inlet-port, the valve H, connected with valve F', and means 85 for moving the valves, substantially as and for the purpose shown.

3. In combination with the inlet-port f, passage h, into which the port f admits steam, in communication with the lifter steam-jet tube, one or more ports, h', leading from passage h and communicating with the force steam-jet 95 tube, the valve F' on the inner or discharge side of port f, and the valve H, connected with valve F' and adapted to close ports h' and keep them closed while the valve F' is moved sufficiently to open port f, and to unclosethem 100 upon further movement of the valves, substantially as and for the purpose set forth.

4. In an injector, in combination with the steam-inlet port f, the passage h, into which the port f admits steam, and the ports h' h', the 105 valve F' on the inner or discharge side of port f, the piston-valve head H, the stem connecting the two valves, and means, substantially as described, for operating the valves, substantially as and for the purpose described.

5. In an injector provided with a steam-inlet-valve opening, a passage communicating therewith and with the lifter steam-jet tube, and a second valve-opening connecting such passage with a passage leading to the force 115 steam-jet tube, a valve controlling the inlet-valve opening located on the discharge side thereof, and a second valve connected with the former and controlling the second valve-opening, and means, substantially as described, for operating the valves, whereby the second valve shall be and remain closed, except when the first or inlet valve is wide open, substantially as and for the purpose set forth.

In testimony that I claim the foregoing I have 125 hereunto set my hand this 27th day of July, A. D. 1886.

CHARLES E. RANDALL.
